UNITED STATES PATENT OFFICE

VICTOR A. ROHLIN, OF PHILADELPHIA, PENNSYLVANIA

SEPARATOR

Application filed March 26, 1927. Serial No. 178,685.

My invention relates to the separation of suspended matter from a gaseous or vapor stream and more particularly to the separation of a suspended liquid, as water, from a vapor, as, for example, steam.

My invention resides in the method of, and apparatus for, causing a gaseous or vapor stream to assume the form of a ribbon or sheet traveling at a relatively high velocity, changing the direction of said sheet to effect the separation of suspended matter, more particularly, a liquid, as water, and thereafter providing separate paths for said separated matter and said stream.

My invention further resides in a method and apparatus of the character above described in which the pressure of the vapor after the removal of a suspended liquid, is increased so that the initial and final pressures of said vapor are substantially equal.

Further, my invention resides in the method of, and apparatus for, progressively increasing the velocity of a gaseous or vapor stream, more particularly in a downward direction, in a path having an increasing rate of change of direction in one direction to effect the separation of suspended matter, more specifically, a liquid, as water, from the stream, providing separate paths for the separated matter and the stream, and thereafter permitting the stream to progressively decrease in velocity, more particularly in an upward direction.

Still further, my invention resides in a method and apparatus of the character above described in which a pressure, substantially equal to the initial pressure of the stream, is created in the outlet passage for the separated matter, and more particularly, in which such a pressure is created by the location of the outlet passage with respect to the stream.

My invention further resides in the method and apparatus hereinafter described and claimed.

For an illustration of a form my invention may take, reference is made to the accompanying drawings, in which:

Fig. 1 is an elevational view, in section, of

my invention as applied to the outlet of a boiler taken on line 1—1 of Fig. 2.

Fig. 2 is an end elevational view, partly in section, of the structure disclosed in Fig. 1 taken on line 2—2 of Fig. 1.

Referring to Fig. 1, the boiler drum 1 is provided with a steam outlet pipe 2 which terminates within the boiler, in an inverted T having each end of its cross-arm open and connected to a separator 3. For convenience but one separator is shown, which in some installations may be sufficient, although it is to be understood that in the illustration herein disclosed and described, two separators which are substantial duplicates are utilized. The curved casing members 4 preferably metal castings, as of iron, are provided at each end with a flange 5 which in each instance determines the position of one of the partition members 6 extending the length of the casing defined by the members 4 and the end caps or plates 7 and 7a, preferably also of cast iron, fastened such as by machine screws 20 to them. The major part of the inner face of the casing 4 is a portion of a curve having a progressively changing radius of curvature, such as, for example, a parabola. The surface of the partition member 6 adjacent the casing is curved and cooperates with the curved inner face of the casing to form a passage 11 of gradually decreasing cross-sectional area from top to bottom. The plate 7a may be dispensed with if the flange of the steam outlet pipe 2 is designed to serve as an end wall of the separator.

An inclined plate 8 having its lower end substantially in alignment with the bottom of a wide slot 15 in the end plate 7 and its higher end substantially in registration with the upper side of the steam outlet opening, extends lengthwise of the casing dividing it into an upper or inlet chamber 16 and a lower or outlet chamber 17. Extending centrally of the plate 8 is a raised portion corresponding in shape to a segment of a hollow cone, dividing it into two troughs 18 which increase in width as they approach the drain opening or slot 15. The outlet chamber 17 is of in-

creasing cross-sectional area as the steam outlet is approached.

As shown more clearly in Fig. 2, the flanges 5 having notches 21 also locate and support a dividing rib member 10 which extends lengthwise of the bottom of the casing and cooperates with the partition members 6 and with the casing members 4 to form two pairs of diverging passages. The passages 12 comprising one pair increase in cross-sectional area as they approach their termination in the outlet chamber 17. The passages 13 comprising the other pair may either discharge directly to the inside of the boiler, to the inside 10 of the boiler through the drip chamber 14 provided with tapped holes 14a, or to a point outside the boiler through pipes, not shown, threaded into the holes 14a. The drip chamber when used is fastened to the lower surface 15 of the separator casing by any suitable means such as machine screws 19. The passages 11 and 12, substantially rectangular in cross-section, form a U-shaped Venturi tube having a throat comprising a longitudinal slit 11a approximately at the lowermost 20 point of the U. The position of the drip port 13 with respect to these passages will be established in the description of the operation of the device.

The main casing of the separator, that is, the separator minus the drip chamber, is always proportioned in practice, so that it may be passed through the man-hole in the boiler in its entirety and need not be assembled 30 within the boiler.

Since the individual separator is symmetrical with respect to the center line 1-1 of Fig. 2, for convenience, the description of operation of the device will be directed to 40 that portion shown in section in Fig. 2. As the steam enters at the top and at the open end of the separator, much of the free water drops upon the inclined plate 8 and is returned to the boiler by the trough 18. The 45 steam and the remaining water traveling at a relatively low velocity enter the mouth 22 of the passage 11. The larger or heavier particles of water strike the curved wall in the region denoted generally by X and flow 50 down it to the drip port 13. Due to the shape of the passage 11, the velocity of the stream increases progressively and in a path having a progressively increasing curvature. As the momentum of the lighter and still 55 lighter water particles increases, due to the increase of the stream velocity, and as the curvature of the path increases, the particles in turn, according to their mass, separate from the stream proper and flow down the 60 curved wall to the drip port. By this consecutive separation of particles according to their mass, and by having the particles striking the wall tangentially, there is no "spattering" 65 due to any direct impact of free water traveling at high velocity, which would or-

dinarily result in the returning of a quantity of separated water to the stream which would then carry it to the outlet as free water. Moreover the separation of each particle is accomplished at the lowest velocity that will 70 accomplish separation of particles of its size, which further reduces the tendency to spatter. The lightest remaining particles are carried across the thin sheet of steam as the passage 75 reverses its direction at or immediately beyond the throat 11a. By positioning the separator as shown so that the velocity is increased in a downward direction and decreased in an upward direction, it is evident that the particles are first given an acceleration in a downward direction by the combined 80 effect of the stream velocity or flow and the relatively small effect of gravity. As the stream reverses its direction, the water particles to be carried to the outlet would have to be given a vertical acceleration in an opposite, that is, an upward direction, by the stream. During the reversal, there is a period in which the particles have no vertical velocity due to 85 the stream, and are traveling in a horizontal path. Gravity, which continues to impart a vertical acceleration to the particles, increases the extent of their downward travel, increases the period of substantially zero vertical velocity due to the stream flow, and retards 90 their acceleration in an upward direction. The net result is that the acceleration of gravity contributes to the separation and makes it 95 possible to realize a higher degree of separation than if the tangential action of the 100 stream alone was utilized.

The passage or drip port 13 which conducts the separated water is so located that the water leaves the steam path immediately after it has attained its highest velocity 105 which may be from 5,000 to 10,000 feet per minute at rated load. It is also so positioned with respect to the curved steam path that it is, in effect, a Pitot tube on the high pressure side of a curved path of flow, and consequently the pressure therein closely approximates the original pressure of the steam. To explain more fully; assuming that the flow is in a straight line, and neglecting friction, the pressure in a Pitot tube is constant 110 regardless of whether it is located in the center of the stream or at a point intermediate the center and the side, and is equal to the sum of the static pressure and velocity head of the stream. Further, if there has been a gradual increase of velocity from the source, the pressure in the Pitot tube is substantially equal to the pressure of the 115 source.

If, however, the flow is in a curved path, 120 the pressure will vary across the width of the stream, being lowest at the side nearest the center of curvature and highest at the opposite side. The centrifugal force created by the change of direction causes a 125

greater stream density at the latter which is indicated by a higher reading in the Pitot tube. It is therefore possible by so placing the tube in a curved stream, to compensate or over-compensate the effect of frictional resistance, so that the pressure produced is practically the same as that of the original source. As the point of high velocity in a Venturi tube is likewise the point of low pressure, it would ordinarily be impractical to effect a transfer from this point to one of higher pressure. However, in my invention by reversing the direction of flow at the throat and in positioning the water discharge passage so that there is a pressure created as above described, it is usually possible to discharge the separated water directly into the boiler. In any event, the difference in pressure is so slight that it may be compensated for by running a short section of pipe from the drip chamber to a point below the surface of the water in the boiler. In either instance, the hot water is returned directly to the boiler so that there is little or no heat loss.

The steam, to all practical purposes devoid of moisture, progressively decreases in velocity as it traverses the passage 12 formed by the wedge-shaped rib member 10 and the upwardly turned extension of partition 6, so that the pressure in the outlet chamber is but slightly less than the initial pressure at the inlet. The dry steam then passes from outlet chamber 17 through pipe 2 to the point of its application to useful work.

While the operation of my separator has been described as applied to the separation of water from steam, its use is not so restricted and the method and structure may be applied in other instances in which it is desired to effect the separation of a solid or a liquid in suspension, from a fluid, either a vapor or a gas. When used for the purpose herein described, the separator is preferably located within the boiler drum, although it is to be understood that it may be elsewhere in the outlet system.

What I claim is:

1. Apparatus for separating moisture from a vapor comprising arcuate members forming fluid passages, each passage having a progressively converging inlet, said arcuate members converging to a narrow slit longitudinally of the axis of said apparatus, and a separating member disposed opposite the discharge ends of said fluid passages and forming with said arcuate members diverging outlets for said vapor and escape outlets for the separated moisture.
2. Apparatus for separating moisture from a vapor comprising sheetlike arcuate members forming fluid passages, said passages first diverging and then converging towards each other, each passage having a progressively converging inlet, said arcuate mem-

bers converging to a narrow slit longitudinally of the axis of said apparatus, and a separating member disposed opposite the discharge ends of said fluid passages and forming with said arcuate members diverging outlets for said vapor and escape outlets for the separated moisture.

3. Apparatus for separating moisture from a vapor comprising arcuate members forming fluid passages, each passage having a progressively converging inlet, a member disposed beneath said inlets and between said passages forming a chamber with the oppositely disposed arcuate members, said arcuate members converging to a narrow slit longitudinally of the axis of said apparatus, and a separating member disposed opposite the discharge ends of said fluid passages and forming with said arcuate members diverging outlets into said chamber and escape outlets for the separated moisture.

4. In apparatus for drying a vapor, arcuate members forming a pair of progressively converging passages, each of said passages converging to a narrow slit longitudinally with respect to the axis of said apparatus and having its concave side facing the other, and means for abruptly changing the direction of flow of said vapor after passing through said slits, said means forming passages with the arcuate members for moisture and dry vapor respectively, the vapor passage having diverging walls.

5. In apparatus for drying a vapor, arcuate walls forming a pair of converging passages, a member extending between said walls and forming therewith the upper wall of a chamber for leading off the dry vapor, said wall being inclined and adapted to drain off excess moisture separated from the vapor before entering said passages, and separating structure forming the lower part of said chamber for separating moisture from the vapor and forming dry vapor passages leading into said chamber.
